UNITED STATES PATENT OFFICE

151,221

DESIGN FOR A SPECTACLE FRAME

Arthur Ditto, Boston, Mass., assignor to Marine
Optical Mfg. Co., Boston, Mass., a partnership

Application November 6, 1947, Serial No. 142,348

Term of patent 14 years

(Cl. D57—1)

To all whom it may concern:

Be it known that I, Arthur Ditto, a citizen of the United States, residing at Roslindale, Boston, in the county of Suffolk and Commonwealth of Massachusetts, have invented a new, original, and ornamental Design for a Spectacle Frame, of which the following is a specification, reference being had to the accompanying drawing, forming part thereof.

Fig. 1 is a plan view of a spectacle frame showing my new design;

Fig. 2 is a side elevational view of the same;

Fig. 3 is a section on line 3—3 of Fig. 2.

The essential features of my design reside in the configuration of the temples shown in full lines.

I claim:

The ornamental design for a spectacle frame, as shown and described.

ARTHUR DITTO.
